UNITED STATES PATENT OFFICE

161,311

RADIO CABINET

Robert D. Budlong, Skokie, Ill., assignor to Win-
charger Corporation, a corporation of Minne-
sota

Application December 23, 1949, Serial No. 6,797

Term of patent 7 years

(Cl. D56—4)

To all whom it may concern:

Be it known that I, Robert D. Budlong, a citizen of the United States, residing at Skokie, in the county of Cook, State of Illinois, have invented a new, original, and ornamental Design for a Radio Cabinet, in which the following is a specification, reference being made to the accompanying drawing, forming a part thereof, wherein:

Figure 1 is a front perspective view of a radio cabinet with the flap dial in an open position, showing my new design;

Figure 2 is a view similar to Figure 1 with the flap dial in a closed position;

Figure 3 is an end perspective view of the cabinet; and

Figure 4 is a fragmentary cross-sectional view of the cabinet taken along line 4—4 in Figure 1.

The end of the cabinet not shown is the same as that which is shown and the back of the cabinet is plain.

I claim:

The ornamental design for a radio cabinet, as shown and described.

ROBERT D. BUDLONG.
